MILLIMETER WAVE GENERATOR

Beverly D. Kumpfer, Spring Lake Heights, N. J.,
assignor to the United States of America as
represented by the Secretary of the Army

Application August 2, 1951, Serial No. 240,023

5 Claims. (Cl. 315—40)

(Granted under Title 35, U. S. Code (1952),
sec. 266)

1

The invention described herein may be manufactured and used by or for the Government for governmental purposes, without the payment of any royalty thereon.

The present invention relates to electron discharge devices of the magnetron type and more particularly to magnetrons for generating electrical oscillation having a wavelength of a few millimeters or less.

In a recent electronic development, the use of a metallic resonant structure in the amplifying mechanism of travelling wave amplifier tubes have been eliminated by employing two interacting electron streams travelling at different velocities. For a description and illustration of this development, reference is made to the publication of "Proceedings of the I. R. E." of January 1949 and to the article entitled "The Electron-Wave Tube" by Andrew V. Haeff.

The most serious obstacle for employing magnetrons for generating oscillations of millimeter wavelength is the apparent necessity to use a plurality of metallic resonant structures of very small dimensions. This requirement arises from the fact that magnetron anode structures have to be arranged so that kinetic energy of electrons can be efficiently converted into the energy of the high frequency electric fields which are supported by these resonant structures. Because of the required reduction in size when operating at millimeter wavelength, the useful output power at millimeter wavelengths of conventional magnetrons is greatly reduced even when maximum emission current densities are approached.

The present invention contemplates and has as a primary object the provision of a magnetron tube of novel design capable of generating electrical oscillations of millimeter wavelength by utilizing two interacting electron streams travelling at different angular velocities.

It is a further object of my invention to provide a magnetron wherein the usual plurality of resonant circuits is effectively replaced by a system of two rotating electron streams which interact with each other.

In accordance with the invention, a magnetron generator comprises a cylindrical anode and a pair of cathodes centrally and axially positioned within said anode. Each cathode is at a discrete potential with respect to the anode to produce two admixed rotating space clouds travelling at different angular velocities in the interaction space.

For a better understanding of the invention, together with other and further objects thereof,

2

reference is had to the following description taken in connection with the accompanying drawing in which:

Figure 1 is a longitudinal sectional view taken substantially through the center of a magnetron made in accordance with the principles of my present invention.

Figure 2 is a transverse sectional view taken along line 2—2 of Figure 1;

Figure 3 illustrates another embodiment of the cathode structure employed in Figure 1; and

Figure 4 is a fragmentary view in cross section illustrating another embodiment of the single resonant structure employed in Figure 1.

Referring now to Figures 1 and 2 of the drawing, there is shown a magnetron 2 comprising an evacuated tubular anode structure 4 made of a cylinder of conducting material, such as copper. The upper and lower ends of cylindrical anode 4 are closed by upper and lower annular end plates 6 and 8 respectively. The end plates are formed of a suitable conducting material such as copper and are hermetically sealed into the ends of anode 4. Depending outwardly from the inner periphery of upper end plate 6 and rigidly brazed thereto, is tubular sleeve 10, the upper end of which is provided with a glass seal 12 for sealing the discharge device after evacuation. Similarly, tubular sleeve 14 depends outwardly from the inner periphery of lower end plate 8 and is provided with glass seal 16.

Centrally and axially positioned within cylindrical anode 4, there is provided two spaced cylindrical cathodes 18 and 20, preferably being of the indirectly heated type, which are identical in construction and axially aligned. Cathode 18, hereinafter referred to as the upper cathode, comprises a cylindrical electronically conductive sleeve 22, preferably made of nickel. Said sleeve is coated externally with an electron emissive material as at 24. Disc-like end shield 26, herein conveniently integral with cathode sleeve 22, is provided proximal end plate 6 to prevent emitted electrons from being projected outwardly toward said end plate.

As a means for supporting upper cathode 18 in position within the tube, there is provided a tubular "Kovar" member 28 which is axially aligned with tubular sleeve 10. As illustrated, one end of tubular member 28 is welded to end shield 26.

A heater 30, which is positioned within upper cathode 18 and which is energized by means of a heating battery 32, serves to maintain coated surface 24 at an emitting temperature. One terminal of the cathode heating element is con-

nected to "Kovar" member 28 by being connected to cathode sleeve 22 and the other terminal is connected to lead-in conductor 34 which extends through aperture 36 of end shield 26, and through "Kovar" tubular member 28. A glass seal 38 between lead-in conductor 34 and tubular member 28 maintains the structure vacuum tight.

Cathode 20, hereinafter referred to as the lower cathode, is identical in construction with upper cathode 18 and is similarly provided with a cylindrical conductive sleeve 40 which is terminated proximal end plate 8 by disc-like end shield 42. Like upper cathode 18, sleeve 40 is coated with an electron emissive material as at 44. Tubular "Kovar" member 46 is provided to support lower cathode 20 in position and maintain it in spaced relationship with upper cathode 18. As shown, tubular member 46 is axially aligned with tubular sleeve 14 which extends outwardly from the inner periphery of lower end plate 8. A heater 47, which is similar to heater 30 supra, is positioned within lower cathode 20 to maintain coated surface 44 at an emitting temperature and is energized by means of heating battery 48 through lead-in conductor 50. Glass seal 52 between lead-in conductor 50 and tubular member 46 maintains the structure vacuum tight.

Cathode 18 is maintained at a negative potential E_1 with respect to anode 4 by means of an appropriate voltage source 54 which is applied to cathode 18 by tubular member 28 through glass seal 12. Similarly, cathode 20 is maintained at a negative potential E_2 with respect to anode 4 by means of voltage source 56 which is applied to cathode 20 through tubular member 46 and glass seal 16. E_1 may be slightly higher than E_2 , or vice versa.

Cylindrical anode 4 is provided with a slot 58 open at both ends and axially parallel to the axis of said cylindrical anode. The depth of slot 58 radially from the inner periphery of anode 4 is preferably chosen to be effectively one-quarter wavelength of the operating frequency so as to provide a resonant cavity therefor. If desirable, slot 58 may be a closed end resonator as shown at 58' in Figure 4, the axial length thereof being effectively one-half wavelength to form a resonant waveguide section at the operating frequency.

In order to take power from the magnetron, cylindrical anode 4 is provided with a second, radially disposed, coupling slot 60, which is coupled and suitably matched to waveguide 62. The depth of slot 60 outwardly from the inner periphery of anode 4 is preferably chosen to be effectively one-half wavelength of the operating frequency. As shown, coupling slot 60 is open at both ends and is axially parallel to the axis of cylindrical anode 4. A glass window 64 sealed into the waveguide maintains the structure vacuum tight. Resonant slot 58 and output slot 60 may be positioned relative to each other along the circumferential periphery of anode 4 in any suitable manner so long as both slots are axially parallel to the axis of the cylindrical anode.

A uniform magnetic field having flux lines extending parallel to the axis of the tube and emitting surfaces of cathodes 18 and 20 is provided by top and bottom cylindrical pole pieces 65 and 66 which may be energized by any of the means well known in the art not shown. Preferably, the flux lines should be concentrated in the interaction space 68, between cathodes 18 and 20 and cylindrical anode 4.

In operation, the discrete electron space clouds from the two cathodes are propagated in the interaction space at discrete angular velocities which may be calculated from the formula

$$V_e = \frac{E}{B}$$

wherein E is the intensity of the electric field in the space between the anode and the cathode and B the value of the constant magnetic field. Thus the electron space cloud from upper cathode 18 travels with an angular velocity

$$V_1 = \frac{E_1}{B}$$

and the electron space cloud from lower cathode 20 travels with an angular velocity

$$V_2 = \frac{E_2}{B}$$

Both electron streams are bunched or density modulated by the single resonant circuit 58 in anode 4 in accordance with conventional magnetron operation. The admixed bunched streams then rotate around the interaction space and interact with each other. As explained by Haeff in the hereinabove mentioned article, the lower velocity stream gains energy from the higher velocity stream in the process of the space charge interaction without the use of a continuous resonant structure. A portion of the amplified energy is coupled out by output coupling slot 60 and the residual energy in the two interacting streams is allowed to feed back around the anode structure to provide regeneration. Since only one resonant structure is required rather than a plurality thereof, the power output at millimeter wavelength operation is greatly increased.

Figure 3 illustrates two identical helically wound filaments 70 and 72 of the directly heated type which may be utilized in place of the cylindrical cathodes 18 and 20. Filaments 70 and 72 are insulated with respect to each other and may be coaxially mounted within and axially aligned with cylindrical anode 4. Voltage E_1 is applied between cathode 70 and cylindrical anode 4 and voltage E_2 is applied between cathode 72 and said anode. The windings of the helically-shaped filaments are so arranged that corresponding windings such as 74 and 76 are superimposed.

While there have been described what at present are considered to be the preferred embodiments of the invention, it will be understood by those skilled in the art that various changes and modifications may be made herein without departing from the invention, and it is, therefore, aimed in the appended claims to cover all such modifications and changes as fall within the spirit and scope of the invention.

What is claimed is:

1. An electron discharge device of the magnetron type comprising a cylindrical anode including a pair of radial slots, a cathode assembly centrally positioned within said anode comprising axially spaced and electrically independent first and second electron emitting surfaces, said electron emitting surfaces being axially aligned with said anode for supplying electrons to the space between said anode and said first and second electron emitting surfaces to produce a first and second electron space cloud, means supporting said electron emitting surfaces in said axial spaced relationship, magnetic means adjacent said anode for producing a constant axial mag-

netic field in the space between said electron emitting surfaces and said anode, means in circuit with said anode and said first electron emitting surface for establishing a first electric field perpendicular to and cooperable with said magnetic field whereby said first electron space cloud is rotated at a first predetermined angular velocity, means in circuit with said anode and said second electron emitting surface for establishing a second electric field perpendicular to and cooperable with said magnetic field whereby said second electron space cloud is rotated at a second predetermined angular velocity.

2. An electron discharge device of the magnetron type comprising a cylindrical anode including a pair of radial slots, said slots being open at both ends and longitudinally parallel to the axis of said anode, a cathode assembly centrally positioned within said anode comprising axially spaced and electrically independent first and second conductive cylindrical sleeves, each of said sleeves being coaxial with said cylindrical anode, means supporting said sleeves in said axial spaced relationship, magnetic means adjacent said anode for producing a constant axial magnetic field in the space between said anode and said cathode assembly, means included in said cathode assembly for supplying electrons to the space between said anode and said first and second sleeves to produce a first and second electron space cloud, means connected between said first sleeve and said anode for establishing a first electric field perpendicular to and cooperable with said magnetic field whereby said first electron space cloud is rotated at a first predetermined angular velocity, means connected between said second sleeve and said anode for establishing a second electric field perpendicular to and cooperable with said magnetic field whereby said second electron space cloud is rotated at a second predetermined angular velocity.

3. A magnetron device comprising a cylindrical anode including a pair of radial slots, said slots being open at both ends and longitudinally parallel to the axis of said anode, a cathode assembly centrally positioned within said anode comprising axially spaced and electrically independent first and second conductive cylindrical sleeves,

each of said sleeves being coaxial with said anode, means supporting said sleeves in said axial spaced relationship, magnetic means adjacent said anode for producing a constant axial magnetic field in the space between said anode and said cathode assembly, means included in said cathode assembly for supplying electrons to the space between said first and second sleeves and said anode to produce a first and second electron space cloud, a first source of direct-current potential coupled between said first sleeve and said anode to establish an electric field perpendicular to and cooperable with said magnetic field whereby said first space cloud is rotated at a first predetermined angular velocity, and a second source of direct-current potential coupled between said second sleeve and said anode to establish an electric field perpendicular to and cooperable with said magnetic field whereby said second space cloud is rotated at a second predetermined angular velocity.

4. The electron discharge device set forth in claim 1 wherein the radial depth of one of said slots is substantially $\frac{1}{4}$ wavelength of the operating frequency and the radial depth of the other of said slots is substantially $\frac{1}{2}$ wavelength of the operating frequency.

5. The electron discharge device set forth in claim 1 wherein said slots are closed at both ends and are substantially $\frac{1}{2}$ wavelength of the operating frequency.
